(57) **CLAIM**

The ornamental design for a pocket light, as shown and described.

DESCRIPTION

FIG. 1 is a front perspective view of a pocket light showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a rear perspective view thereof showing a first unfolded state;

FIG. 10 is a front perspective view thereof showing the first unfolded state;

FIG. 11 is a front perspective view thereof showing a second unfolded state;

FIG. 12 is a rear perspective view thereof showing the second unfolded state;

FIG. 13 is a front perspective view thereof showing a third unfolded state;

FIG. 14 is a rear perspective view thereof showing the third unfolded state;

FIG. 15 is a partial enlarged view taken from circle 15 in FIG. 1; and,

FIG. 16 is a partial enlarged view taken from circle 16 in FIG. 1.

The dash-dash broken lines in the drawings illustrate portions of the pocket light that form no part of the claimed design.

The dot-dash broken lines in the drawings depict the boundaries of the partial enlarged views that form no part of the claimed design.

1 Claim, 16 Drawing Sheets
